Inventor
John K. DeLoach.

By *Freaco C. Hender*
Attorney

UNITED STATES PATENT OFFICE.

JOHN K. DE LOACH, OF ATLANTA, GEORGIA.

INDEX FILE.

Application filed May 21, 1924, Serial No. 714,876. Renewed August 20, 1926.

This invention relates to new and useful improvements in filing devices.

One object of the invention is to provide a filing device wherein cards, letter folders, or the like, are used and wherein, regardless of the fact that the cards, etc., are arranged in a predetermined order, as for instance, in alphabetical order, certain cards, according to their classification and regardless of their position in the predetermined order, may be lifted above their fellows without disturbing said fellows, so that the indexes of said lifted cards will be visible and following the predetermined order.

Another object is to provide a filing device wherein cards, letter folders, or the like, are used, and wherein special alphabetical or other index cards are dispensed with and service cards, that make up the complete contents of the file, used in as great or as small profusion as may be needful for the most complete visible indexing at a corresponding saving in space and material.

Another object is to provide a file box for containing the cards, or the like, having means arranged to cooperate with all cards of one classification upon movement in one direction and to cooperate with all cards of another classification, upon movement in the other direction, whereby the number of operating means is reduced to the minimum.

A further object of the invention is to so construct and arrange the file box, with its card operating means, and the cards, that when the operating means is moved to elevate a group of cards of a certain classification, said operating means will engage with portions of the remaining cards to limit the movement of operating means in that direction.

A further object of the invention is to so construct and arrange the file box that a side wall shall be the full height of the cards, smoothly finished to reduce friction, and accurately spaced so that the cards are free to move smoothly up and down between them and yet not loosely. This obviates the tendency of the cards to cock or bind as would happen in a file with skeletonized or cut down sides when cards are raised in the manner herein described.

A still further object is to provide a file box which is so constructed that the cards will be supported in a vertical position by partitions or walls, which may be either

fixed or movable, and spaced at intervals throughout the length of the file box, and thereby obviate the use of the usual follower boards, and permit the cards of the several batches to be relieved of the weight of the remaining cards, with the result that the cards will be lifted with greater ease, and manual accessibility permitted.

Other objects and advantages will be apparent from the following description when taken in connection with the accompanying drawings.

In the drawings:

Figure 1 is a top plan view of a file box containing cards, and made in accordance with the invention.

Figure 2 is a vertical longitudinal sectional view on the line 2—2 of Figure 1.

Figure 3 is vertical transverse sectional view on the line 3—3 of Figure 1.

Figure 4 is a front elevation of the file box.

Figure 5 is a view of one of the cards.

Figure 6 is a vertical transverse sectional view through a card box showing the use of cards retained by longitudinal rods.

Referring particularly to the accompanying drawing, 10 represents an elongated box, of a construction somewhat similar to the ordinary card index boxes or drawers now in use, with modifications to adapt the same to the present invention. Secured to the bottom of the box, and extending along the side walls thereof, are the strips 11, and formed transversely in each of the strips are the grooves 12, similar grooves 13 being formed in the side walls of the box, extending vertically in the inner faces thereof, and communicating with the grooves 12. In these grooves 12 and 13 are secured the vertical walls 14, the lower ends of which are the same width as that of the strip, while the upper ends are slightly narrower and project slightly lower than the top edges of the cards before they are elevated. Secured in the rear end wall of the box, below the upper faces of the strips 11, and above the bottom of the box, are the bushings 15, while similar bushings 16 are secured in the front wall of the box at the same elevation, and a longitudinal alignment with the bushings 15. Rotatably supported in these bushings 15 and 16 are the end portions of the crank shafts 17, and crank portions 18 of

which extend throughout the length of the 110

- box. Secured on the outer face of the front wall of the box, above the adjacent ends of the shafts 17, and having openings receiving the said ends therethrough, is a metal plate 19. On this plate, above the shaft ends, are numbers from 0 to 9, and each shaft is provided with a button or knob 20, which is adapted to be grasped to rotate the shaft.
- 10 The cards, one of which is indicated by the number 21, in Figure 5, are placed in batches, between the walls or partitions 14, so that the cards will be readily accessible by hand, and also that they will be relieved of the weight of the entire number of cards as is experienced in the usual card index boxes now in use. Printed on the card, adjacent to the lower edge of the card are numerals from 0 to 9. These numerals are spaced apart so that a tab 22 may be secured to the card to cover any one of the numerals, said tab projecting below the lower edge of the card. These numerals are positioned as a guide for the proper placing of the tab, and for a purpose that will presently be described more in detail.

The cards will be printed in blank form to be filled in with such data as will bring the cards under different classifications. As 30 a concrete example, the card illustrated is used in the automobile business, in which the dealer handles new and second hand cars of different makes and the cars may be indexed under any one or several of the following classes: 0—Alphabetical index of car owners; 1—Buicks; 2—Cadillacs; 3—Chevrolets; 4—Essex; 5—Fords; 6—Maxwells; 7—Miscellaneous; 8—Special bargains; 9—Liberal terms. The card illustrated in the 40 drawing has three tabs projecting from the lower edge, that before mentioned as 22, and the additional tabs 23 and 24. While the tab 22 covers the "0", the tabs 23 and 24 cover the "5" and "9" respectively. This 45 would indicate that the card fell under the three classes, namely, the name of the owner, a Ford; and that it could be bought on liberal terms. While the particular card illustrated has three tabs, it will be understood that other cards may have only one tab, or may have a greater number that would place them in more than three classes. Furthermore, it is apparent that if the 50 names of all owners are placed in the file 55 in alphabetical order, the names of the selected group of Ford owners will appear in alphabetical order when those cards are raised to visibility. Furthermore it is apparent that no special alphabetical or other 60 index cards are needed as the service cards themselves when raised to visibility so that each car owner can be read in alphabetical order, serve as a visible index.

The lower ends of the tabs are arranged 65 to lie above, and at one side of a crank por-

tion 18, so that when the shaft is rotated in one direction the crank will engage with the lower end of the tab of one card and lift the card above the remaining cards in the box, while upon turning the shaft 70 in the other direction, the crank will engage with the tab of another card and elevate said card above the others. It will thus be seen that upon rotating a shaft, the crank portion will elevate all cards 75 of a certain classification in the entire box above the remaining cards so that the entire classification of cards can be simultaneously inspected.

Suppose the dealer wishes to advertise all 80 the special bargains and to get these quickly he turns the shaft beneath the "8" toward the left, which causes the crank portion of that shaft to engage the tabs of all cards which are in the class of "Special 85 bargains," and lift the cards above the remaining cards in the box. The dealer can then ascertain from these cards, the names of the owners in alphabetical order, the names of the cars, prices, terms and the 90 like information.

Printed in the upper right hand corner of each card is another series of numbers from 0 to 9 similar to that printed on the bottom edge of the card, except smaller and 95 more condensed. When any particular classification of cards is raised to visibility these numbers are visible on each of the raised cards and appear in more or less regular columns to the operator. That is, 100 all 0's appear in orderly fashion, one above another and similarly the "1"—"2"—"3"—"4"—"5"—"6"—"7"—"8"— and "9" of each 105 card. It is apparent that if any of these numbers on any card are marked, as for instance by a cross mark with a lead pencil, it will be instantly visible and this gives a sub-classification of ten for each of the main classifications or ten times ten or one hundred classifications in all. Furthermore, by 110 the use of a collection of cards in ten different colors or by the use of signals of any kind in ten different colors or by the use of a large signal number to the left of the series 115 of numbers in the upper right hand corner, as indicated in Figure 5 of the drawing, said signal numbers ranging from "0" to "9", it will be seen that a further subdivision 120 of ten can be had thus giving ten times ten times ten or one thousand classifications for visible indexing. It is also apparent that by increasing or decreasing the number of ten primary classifications with a corresponding change in the first and second sub-classifications, the resultant total number of 125 classifications will vary as the cube of the numbers concerned. Thus with twenty tabbed spaces and twenty primary signals and twenty secondary signal numbers there 130 results $20 \times 20 \times 20$ or 8000 total possible

classifications. It is claimed for this system of multiple visible indexing that it is much quicker, more complete and less fatiguing to the mind and eye of the operator than other systems.

Particular attention is called to the fact that the partitions 14 divide the cards into batches, each of which includes a number of cards which will more or less loosely lie between the partitions, and permit ready manipulations without the operation of the shafts 17. This also permits the cards of the different classes to be elevated without drawing other cards upward therewith. Furthermore, the tabs are secured in such a manner that they space the cards to a sufficient degree to permit air spaces therebetween, thereby permitting the cards to more easily move upwardly without disturbing the others.

Attention is also directed to the fact that the crank portions 18 are limited in their movements, after having engaged and lifted certain cards, by the tabs of adjacent remaining cards, in either direction of movement of the shafts.

All of the above relates to the common system of filing whereby cards, correspondence or other records are removable at will from the file. Protection is also asked in this application for patent for the use of my device in that also common system of filing whereby cards, correspondence or other records are not removable at will from the file. I refer particularly to such systems as the card index system of public libraries wherein the cards, for obvious reasons, cannot be removed by the general public.

As shown in Figure 6, the box is provided with a pair of longitudinal rods 25 which pass through the vertically disposed elongated slots 26 formed in the cards adjacent the ends thereof, said slots permitting a limited vertical movement of the cards

while at the same time prevent removal of the cards from the box.

What is claimed is:

1. An index system including a container, cards in the container having depending tabs, means for holding the cards in separate groups, each group of cards including cards of different classifications, the tabs of the cards of corresponding classifications being in alignment longitudinally of the container, and lifting means movable in one direction to engage longitudinally aligned tabs of cards of one class to elevate same and in the opposite direction to engage longitudinally aligned tabs of cards of another class. 50

2. An index system including a container, cards in the container having depending tabs, means for holding the cards in separate groups, each group of cards including cards of different classifications, the tabs of the cards of corresponding classifications being in alignment longitudinally of the container, and a rockable lifting means beneath the tabs and movable in one direction to engage the aligned tabs of one classification of 55 cards to elevate same and in the other direction to engage the aligned tabs of another classification of cards to elevate the same. 60

3. An index system including a container, cards in the container having depending tabs, means for holding the cards in separate groups, each group of cards including cards of different classifications and having their tabs in alignment longitudinally of the container, and cranks beneath the tabs and arranged to be rocked in one direction to engage the aligned tabs of cards of one classification and in the other direction to engage the aligned tabs of another classification, to elevate said cards above the others, the aligned tabs of each classification of cards serving as stops for limiting the rocking movements of the cranks. 70

In testimony whereof, I affix my signature.
JOHN K. DE LOACH.
